UNITED STATES PATENT OFFICE.

WILLIAM N. MARSDEN AND THOMAS E. FLOYD, OF AMSTERDAM,
NEW YORK.

DESIGN FOR A GLOVE-PATTERN.

SPECIFICATION forming part of Design No. 25,980, dated September 1, 1896.

Application filed March 19, 1896. Serial No. 583,980. Term of patent 14 years.

To all whom it may concern:

Be it known that we, WILLIAM N. MARSDEN and THOMAS E. FLOYD, citizens of the United States, residing at Amsterdam, county of Montgomery, and State of New York, have 5 invented and produced a new and original Design for a Pattern or Blank for Gloves, of which the following is a specification, reference being had to the accompanying drawing, the figure of which represents a blank or pattern for a glove containing our design.

This blank or pattern comprises the rectangular body provided with finger-lengths and the thumb-piece, each having an aperture 15 in the form of a quadrilateral, curvilinear figure A located within its tip.

The essential feature of the design is the blank or pattern for the digital portions of a glove having in their tips an aperture in the form of a quadrilateral, curvilinear figure, as 20 shown.

What we claim as new, and desire to secure by Letters Patent, is—

The design for the pattern or blank for a glove as herein shown and described. 25

In testimony whereof we have hereunto set our hands this 13th day of March, 1896.

WILLIAM N. MARSDEN.
THOMAS E. FLOYD.
